INVENTOR:

H. A. W. Maercklein
BY *Munn & Co.*
ATTORNEYS.

UNITED STATES PATENT OFFICE.

HERMAN A. W. MAERCKLEIN, OF HARTFORD, CONNECTICUT.

SOFA-BED.

SPECIFICATION forming part of Letters Patent No. 247,933, dated October 4, 1881.

Application filed April 20, 1881. (No model.)

To all whom it may concern:

Be it known that I, HERMAN A. W. MAERCKLEIN, of Hartford, in the county of Hartford and State of Connecticut, have invented a new 5 and useful Improvement in Sofa-Beds, of which the following is a specification.

Figure 1 is a plan view of the sofa opened to serve as a bed, one folding bolster only being thrown back on its hinge. Fig. 2 is an end 10 elevation of my sofa-bed closed. Fig. 3 is a back sectional elevation of one end of the sofa. Fig. 4 is a front elevation of one end of the sofa.

Similar letters of reference indicate corresponding parts.

15 The object of my invention is to provide an improved combined sofa and bed which shall be free from complicated devices for adapting it for use as a sofa or a bed, and which may be so adapted without unduly stretching or crowding its upholstery.

20 My invention consists in the means provided for retaining and releasing the back of the sofa to adapt it for use as a bed, and in the relative arrangement of the parts to preserve its upholstery in good condition, and in the method of hinging the end bolsters to the side arms of the sofa to avoid the appearance of a hinge-joint at its front.

I more particularly describe my invention as 25 follows:

The drawings representing my improvements show in Fig. 1 the sofa opened for use as a bed, its back A being lowered on hinges *a* to bring it in the same plane with the seat B. One of the hinged bolsters C is shown swung over on 30 the lowered back A, the other end bolster C not being thrown over, in order to show the hinged plate or leaf D'. The fixed framework F supports the bottom or seat B and stationary arms G of the sofa, its back ends extending past the back of the arms G, as at F'. The sofa is supported on suitable legs, H, a draw, I, sliding in guides between them, which serves as a receptacle for bed-clothing. Both 35 legs H and drawer I are provided with casters *i*. Said drawer I can be drawn out a limited distance from the back of the sofa, being stopped by the blocks *o*, secured to the frame F, and when so drawn out, as in Fig. 2, its 40 front supports the outer edge of the back A, to hold it in a horizontal position, as in Fig. 1.

The plates D', which are hinged at *d* to both endframes D, of the sofa-back, act, when closed,

as in full lines in Fig. 3, to support the back A in a vertical position, and when so closed the 55 plates D' form a continuation of or flush finish with said end frames, D, and may be locked in such closed position by any suitable device, as at *d'*. To lower the back A, as in Fig. 1, the said plates D' must first be lowered on their 60 hinges *d*, when the back may be brought to the horizontal position to rest on the lower frame-bar, F², and on the front of the drawer I. The end bolsters, C, are hinged at their backs, as at 65 *c*, their fronts closing on the stationary arms G and making a joint therewith at the front, behind the frames G' of the stationary arms G, as shown in dotted lines in Fig. 4, thus making a neat finish without showing a hinge-joint at 70 the front of the sofa.

As will appear in Fig. 3, the back A is hinged at *a* to the back uprights of the stationary arms at a line about even with the tops of the springs J in the seat or at the center of the upholstery, which prevents the rising and lowering movements of the back, unduly stretching or crowding the springs and other upholstery of the seat and back, and insuring their original 75 smoothness of finish for a long period.

My combined sofa-bed is thus adapted for 80 use either as a sofa or a bed without requiring the adjustment of complicated devices, and its movements are simple and positive.

Having thus fully described my invention, I claim as new and desire to secure by Letters Pat- 85 ent—

1. In combination with the hinged back A and frames F, the hinged plates D', adapted to hold said back A in a vertical position and to be lowered to permit the back to be brought 90 to a horizontal position, substantially as described.

2. The combination, with stationary sofa-arms, of the bolsters C, hinged thereto at their rear ends, and the lowering back A, as shown 95 and described.

3. The back A, connected with the seat B by hinges *a* with pin-joints on a line with the tops of the springs J in the seat, to prevent unduly crowding and stretching said springs, as de- 100 scribed.

HERMAN AUGUST WILHELM MAERCKLEIN.
